ATTORNEY

UNITED STATES PATENT OFFICE.

JAMES CURRAN, OF PORTLAND, OREGON.

ANTI-INDUCTION DEVICE.

SPECIFICATION forming part of Letters Patent No. 371,555, dated October 18, 1887.

Application filed April 13, 1887. Serial No. 234,673. (No model.)

To all whom it may concern:

Be it known that I, JAMES CURRAN, a citizen of the United States, residing in Portland, in the county of Multnomah and State of Oregon, have invented certain new and useful Improvements in Anti-Induction Devices; and I do hereby declare that the following is a full, clear, and exact description of my invention, such as will enable others skilled in the art to 10 which it appertains to make and use the same.

My invention is especially designed for use at the central office of a telephone-exchange; and its object is to counteract wholly or in part the effects of currents induced by electric- 15 light or power currents.

To this end it consists, broadly, in providing means whereby the connection between any two subscribers' lines can be made by means of a loop which is exposed to the influence of the same disturbing source as that which affects the telephone-circuit. The loop is furnished with a switch for presenting the polarity of the loop in opposition to that which is induced on the telephone circuit, and also 20 with a second switch, which regulates the influence of the loop by connecting its sides through a variable resistance or joining them directly, and so short-circuiting the larger portion of the loop.

25 The loop may be excited by being exposed to the disturbing influence either under the same conditions as the telephone-wires themselves or by forming the secondary of an induction-coil of which the primary is either a part of the original disturbing-circuit or a wire strongly influenced by it.

The construction in which my invention is embodied is illustrated in the accompanying drawings, in which—

30 Figure 1 shows a diagram of my circuits and apparatus, and Fig. 2 illustrates a modified arrangement.

Referring to the drawings by letter, A is a 35 switch-board in the central office of a telephone-exchange. 1, 2, 3, 4, 5, and 6 are telephone-wires connected to the said switch-board. 15 is a wire carrying a powerful current for the purposes of electric light or power. The wire 1 runs for a considerable distance in 40 close proximity to the wire 15, and by reason of its proximity has induced in it a current

which affects injuriously the working of the line. The wires 2, 3, 4, 5, and 6 also run parallel to the wire 15 and are injuriously affected in different degrees, according to their distance 55 from the disturbing-wire. Another series of wires, 7, 8, 9, 10, 11, and 12, pass to the switch-board A from such a direction as to be practically unaffected by the current on the wire 15.

If, now, I connect the wire 1 directly through 60 the switch-board with the wire 10, communication by telephone through the circuit thus made will be subject to the well-known disturbances caused by induced currents. To obviate this I introduce between the two lines 65 to be connected a loop, 13 14, the said loop being provided with the usual plugs and flexible cords for making connection at the switch-board. I run the loop along in proximity to the wire 15, and thus subject it to substantially the same conditions as affect the telephone-wires 1 2 3 4 5 6. Having run the wire for a considerable distance, as described, I turn it away from the wire 15 and lead it back by a quiet route to the central office. I find 70 in practice that by inserting a loop arranged as described between two telephone-lines and opposing the polarity of the loop to that induced in the telephone-circuit by the disturbing source I reduce greatly the injurious effects 75 of the induced current. It is of course necessary to provide apparatus for presenting the loop with different polarities to line. Accordingly I locate in a convenient position a four-point switch, B, having the well-understood 80 connections for reversing the polarity. I also place in the loop-circuit a second switch, C, and a series of resistances, D. By means of the switch C and the resistances I can regulate the influence of the loop. More or less 85 resistance will be included in the loop-circuit, according as the switch-arm is turned to the left or right. If the switch is turned over on the stop E, the major part of the loop will be short-circuited. An operator can manipulate 90 the switches B and C according to circumstances to meet the various needs of telephone service. If he is to connect two undisturbed lines, the switch C will be turned to the stop E, or the connection will be made through the 95 switch-board in the ordinary manner.

In Fig. 2 I have shown the wire 15 forming

the primary of an induction-coil and the loop 13 and 14 forming the secondary thereof. This may be found advantageous where it is possible to bring in the wire carrying heavy currents and make it form the primary of an induction-coil, as illustrated. In many cases this would not be practicable, and, in general, I prefer the arrangement illustrated in Fig. 1. I do not wish, however, to limit myself to that arrangement. Nor do I wish to confine myself to the use of my anti induction device in connection with telephone-lines alone. It may be used advantageously in ordinary telegraphic service, although I expect to apply it chiefly 15 to the use I have described.

Having now described my invention, what I claim is—

1. The combination, with a telephonic or telegraphic circuit and a disturbing-line in inductive proximity thereto, of a loop exposed to the influence of the same disturbing-line, and means for connecting up the loop in the telephonic or telegraphic circuit, the said loop containing pole-changing devices, as and for 25 the purpose set forth.

2. The combination, with a telephonic or telegraphic circuit and a disturbing-line in inductive proximity thereto, of a loop exposed to the influence of the same disturbing-line, and means for connecting up the loop in the 30 telephonic or telegraphic circuit, the said loop containing pole-changing devices and an adjustable resistance, as and for the purpose set forth.

3. The combination, with a number of telephonic circuits and one or more disturbing-lines in inductive proximity thereto, of a loop exposed to the influence of the same disturbing line or lines, the said loop being provided with means for making connection between 40 any two of the telephonic circuits, as and for the purpose set forth.

In witness whereof I have hereunto signed my name in the presence of two subscribing witnesses.

JAMES CURRAN.
